UNITED STATES PATENT OFFICE.

JOHN GIDEON KIRKSEY, OF SEATTLE, WASHINGTON.

APPARATUS FOR WASHING AND SIZING.

1,179,842.

Specification of Letters Patent. Patented Apr. 18, 1916.

Application filed February 15, 1915. Serial No. 8,339.

To all whom it may concern:

Be it known that I, JOHN G. KIRKSEY, a citizen of the United States, residing at Seattle, in the county of King and State of Washington, have invented certain new and useful Improvements in Apparatus for Washing and Sizing Such Material as May be Adapted to Separation into Different Sizes, of which the following is a specification, reference being had therein to the accompanying drawings.

This invention relates to certain new and useful improvements in apparatus for sizing or classifying material, either in a dry or wet state, or with or without using water, as the material comes from coal and placer mines or other adapted material, and giving as many different sizes as there would be screens employed in the construction, even down to a very fine mesh or size as might be desired.

Another object of my invention is to provide an apparatus, by means of which a far greater tonnage of material can be sized in a given time than with other classes of sizing machines and at a greatly reduced cost per ton for sizing, with a minimum of horse power to operate same, with low cost of upkeep, and giving a plurality of sizes for separate and better treatment—as in ore mills and for concrete work.

Another object of my invention is to provide an apparatus whereby the material, on the highly inclined screen cloths is given a very rapid travel, due to the rapid cushioned jar or deadened percussion stroke given to the screen carrying frame, and which gives a rapid bouncing downward movement to the material in passing over the screens, thus practically overcoming the scour, friction and wear of the screen cloths, thus giving longer life to the screen cloths, and also avoiding the clogging of the screen meshes.

Another object is to mount one above the other, a plurality of screens of different mesh, the coarsest being the topmost, or one first receiving the material, with each succeeding lower screen of finer mesh, and in such manner of construction that each upper screen will discharge the material passing therethrough onto the head or high end of the one next below, and so on through the series, so as to occupy or require but little floor space for such apparatus.

Another and further object of my invention is to provide a machine with a plurality of different sized mesh screens, thereby giving larger tonnage capacity, with few or practically no moving or wear parts, and one with which the associated fine or comminuted material can be readily separated.

Other and further objects and advantages, presented in this improvement will be made manifest in considering the following details of construction, in connection with the accompanying drawings.

Figure 1, is a perspective view of my improved device, as would be mounted for treatment of certain classes of material. Fig. 2, is a perspective view of the spring supported metal frame, with contained removable screen carrying pans or receptacles. Fig. 3, is a vertical side sectional view of same. Fig. 4, is a perspective view of the removable screen carrying pan, with parts broken away. Fig. 5, is a broken vertical side section, showing the stationary feed conveying pans or launders, leading to the uppermost screen of the operable inner metal frame.

Like numerals of reference refer to like parts in the several drawings.

Referring to the drawings 1 denotes the base members, 2 the uprights, 3 the intermediate side members and 4 the upper members comprising the main or heavy outer frame in which is mounted the inner metal or screen frame.

5 designates the superposed inclined hopper frame attached to the outer frame aforesaid and 6 the side frame members supporting the operating shaft for this apparatus hereinafter more particularly described.

7, is a platform shown—partly broken—upon which to stand to regulate the wash water and operate the hinged adjustable grizzly, when such is used.

8, are rods for more securely holding together the wooden frame.

Water supply pipes 9, provided with a plurality of controlling valves 10 are mounted upon the frame and held in position in any desired manner, as by means of clips 11, said supply pipes being provided with lateral apertured branches arranged in proper position with respect to the grizzly and screen members hereinafter described, being provided with closing caps 12, whereby the larger pieces of the material which fail

to pass through the grizzly and the screens may be washed into connecting launders, not shown.

13, are the box bearings in which are mounted the crank shaft 14, with ratchet and pawl 15, designed for adjusting to different angles the hinged grizzly 17, by means of the connecting wire ropes 16.

18, is a metal hopper, surmounting and supported on the wooden inclined frame and into which the material is first delivered for treatment.

19, are metal aprons fastened to the wood frame to receive the oversize from each screen and carry the same to connecting launders, not shown.

20, are heavy metal sheets, reinforced with the heavy angle bars 21, and held together by like cross angle bars, thus forming a rectilinear frame, which is vertically supported on springs 22, having also connecting rods 26, and auxiliary adjustable coil springs 23.

24, are pieces of steel riveted to cross angles 21, on which the involute wheels 36 coat.

25, are resilient cushions—preferably rubber, fastened on the cross bars 21, which are made to strike similar corresponding cushions fastened underneath timbers 4, these cushions producing a resilient action to the spring supported inner frame, when operated.

27, are openings cut in the sides of the frame, through which the shaft 35 passes.

28, are removable metal receptacles or pans carrying screen cloths of different mesh and adapted to be bolted to and made part of the said resilient inner frame represented by Fig. 2, with bolts 42. Said pans carry the spacing and supporting pipes or flanges 29 on which rest the screen cloths 31, with corresponding longer pipes or flanges 30 above the screen cloths, said cloths and pipes being fastened to said pans by bolts 32 and the projecting ends of the screen cloths being further secured to pipes 30 by the U bolts 33, as clearly shown in Fig. 3.

50 34, are angles riveted near the lower bottom edge of the pans for greater rigidity and strength.

35, is a shaft mounted in bearing boxes 38, attached to the wood members 6, and 55 which shaft carries the involute wheels 36 and pulleys 37.

39 and 40, are stationary inclined pans, provided with spacing pipes or flanges 43, forming channels, corresponding with the 60 screen pan channels and adapted to conduct the material from the grizzly to the upper end of the topmost screen in said resilient frame, said material going into each space or channel between such pipes or flanges passes to a corresponding space or

channel in said screens, and so on throughout the series of screens, thus securing an even distribution of the material over each screen and pan. I preferably employ metal pipes for such spacing and securing of the 70 screen cloths in the pans, as they are light and strong, the contact surface between such and the screen cloths is very little, and the rounded surface of the pipes presents no sharp corners to wear the screen cloths, but 75 it will be understood that I do not limit my invention to the use of such, as other forms could be used.

In the embodiment illustrated a plurality of screen carrying inclined pans are shown 80 disposed one above the other and bolted to the spring supported operable metal frame, thus permitting of their easy removal for repairs or change of screen cloths. These pans are fixed at a very considerable downwardly inclination, to give rapid travel to the material and in such manner that the material passing through each screen cloth is discharged directly from the lower edge of the shortened bottom of the pan onto the 85 head or high end of the screened pan next below, the channels formed in the pans by the flanges or pipes supporting and holding down the screen cloths, discharge into the corresponding channel of the next lower 90 screen pan, and so on through the series thus preserving a uniform distribution of the material through the machine.

As will be observed, one of the novel and valuable features of this invention are the 100 screen carrying receptacles or box like pans, wherein the bottom of the pan stops short of its sides and also the end of the screen cloth and upper pipes, thus producing an opening between the bottom of the pan and the head of the next contacting lower pan, and through which the material that passes 105 through the screen goes directly to the head end of the screen next below, while the oversize is carried farther and passes out over the fixed aprons. Thus a direct, co-operative, continuous connection between the plurality of screens is secured with a resultant 110 oversize from each screen, and an undersize from the lowermost screen.

In the embodiment illustrated I show 115 four screens, but it will be understood that I do not limit myself to a fixed number of such, as the character of the material to be treated or the number of sizes desired would 120 control the number of screens used; but obviously the greater the number of screens used, the greater will be the tonnage capacity of such machine, provided the 125 meshes or openings of the screen cloths be of such selection as that each screen will carry off about the same percentage of oversize; so, under this novel construction, a large number of screens can be used in the same frame, within a height practical for 130

operation. As will be seen, this operable screen carrying inner frame is mounted vertically preferably on carriage springs of sufficient strength to sustain the weight and cause a moderate contact or impingement between the resilient cushions at the top, so with the auxiliary coiled springs the force of the down stroke of said frame can be most delicately governed, while the length of such stroke is regulated as between the contact faces of the involute wheels and the plates fixed on said frame, against which said wheels contact or coat. If the stroke be too long, some of the spacing packing between the shaft boxes and timber support may be removed, thus raising the shaft and involute wheels. It will also be observed that this spring supported inner frame is in, practically perfectly balance, in operation, hence presents no lateral movement and but slight friction and wear of the short retaining contact plates, near the tops of the inner and outer frames.

While I preferably employ the surmounted hopper and its connections, it is apparent that same could be dispensed with, where washing be not desired and the material may be delivered direct to the head of the uppermost screen.

As elsewhere stated, this apparatus is adapted to handle material in either a wet or dry state or with or without water, but I preferably employ water as the travel and tonnage capacity is greatly increased and better results secured.

In the operation of this apparatus, which is especially well adapted to the handling of placer mine material, such product, being sent to the hopper by various means, is usually made up of boulders and pieces of rock too large to pass through the grizzly, so the adjustably grizzly is set at the desired angle to hold the material in the hopper, when a graduated water spray is turned on, giving a graduated feed to the machine, and when the larger rock is washed of its adhering material and ore, the grizzly is lowered to the same plane as the hopper bottom, when the washed oversizes will pass by gravity into connecting launders and to the waste dump, while the respective sizes from the screens go to devices calculated to save the contained values.

It is to be understood that I do not limit or confine myself to the details of construction herein shown and described, inasmuch as various minor changes, such as would suggest themselves to the skilled mechanic, may be made therein without departing from the spirit or fundamental principles of my invention.

I claim as my invention:

1. A sizing machine of the class described comprising a main frame, a screen frame mounted for reciprocation thereon, means

for reciprocating the screen frame, a resilient support for said screen frame, and resilient control means intermediate the said frames and independent of the resilient support for regulating the force of the reciprocatory movement. 70

2. A sizing machine of the class described comprising an outer main frame, and inner screen frame mounted for reciprocation thereon, a resilient support for the screen frame, means for actuating said inner frame, and oppositely disposed adjustable means intermediate the frames for balancing the resilient motion of the screen frame. 75

3. A sizing machine of the class described comprising a main frame, a spring supported screen frame mounted therein, means for reciprocating the screen frame, means for regulating the resilient action of the screen frame comprising an auxiliary spring, and an adjustable connection between the frames coacting with the auxiliary spring for adjusting the latter. 80 85

4. A sizing machine of the class described comprising a main frame, a screen frame mounted for reciprocation thereon, means for reciprocating the screen frame, a resilient support for said screen frame, resilient control means intermediate the said frames and independent of the resilient support for regulating the force of the reciprocatory movement, and a yieldable buffer disposed opposite to the resilient support aforesaid against which the screen frame is adapted to impinge. 90 95 100

5. A sizing machine of the class described comprising a main frame, a spring supported screen frame mounted therein, means for reciprocating the screen frame comprising an operating shaft extending transversely of the main frame and passing through the screen frame, a cam member mounted upon said shaft and coacting with the main frame whereby upon rotation of said shaft to impart reciprocatory movement to the inner frame, a driving pulley connected to said shaft for actuating the latter, and means for controlling the force of the resilient movement of the inner frame. 105 110

6. In a sizing machine of the class described, the combination with screening or assorting mechanism, of means for supplying material to be operated upon to said mechanism, and adjustable retarding means intermediate the screening and supply means arranged to receive thereupon the material from the latter and hold the same temporarily, whereby the material may be acted upon preliminary to passing to the screening mechanism. 115 120 125

7. In a sizing machine of the class described, the combination with screening or assorting mechanism, of means for supplying material to be operated upon to said mechanism, a grizzly intermediate the 130

screening and supply means to receive thereupon the material from the latter and movable to the same plane as the supply means for discharging the material, and means for 5 adjusting the grizzly to control the passage of the material therefrom to the screening mechanism.

8. In a sizing apparatus of the class described, the combination of a hopper, screening mechanism, a retarding member pivotally mounted intermediate the hopper and said screening mechanism, and means connected to the free end of the retarding member for adjusting its inclination whereby to 10 hold the material passing from the hopper temporarily during action thereupon preliminary to passage of the material to the screening mechanism.

9. In a sizing machine of the class described, the combination of a hopper, screening mechanism, a retarding member pivotally mounted intermediate the hopper and said screening mechanism, means connected to the free end of the retarding member for 20 adjusting its inclination whereby to hold the material passing from the hopper temporarily during action thereupon preliminary to passage of the material to the screening mechanism, and washing means associated 25 with the retarding member for separating the material to be screened from the material supplied by the hopper during the retarding action.

10. In a sizing machine of the class described, the combination of a main frame, a superposed inclined frame, a hopper supported by the inclined frame, a screen frame movably mounted in the main frame beneath the hopper, a grizzly pivotally secured adjacent to the discharge opening of 30

the hopper, and adjusting means for said grizzly comprising a crank shaft, connecting members connected to the free end of the grizzly and the crank shaft and adapted to be wound upon the latter for adjusting the 45 inclination of said grizzly, and means for holding the crank shaft at adjusted positions.

11. In an apparatus, for sizing coal, gravel, crushed rock and other material; 50 comprising an outer frame; an inner metal frame mounted on springs attached to said outer frame; auxiliary springs adapted to control the force of the stroke between the inner and outer frames; said inner frame 55 having secured therein a plurality of removable inclined screen carrying pans, disposed one above the other, the uppermost pan adapted to discharge the material passing therethrough onto the upper end of the 60 pan next below, and so on through the series; screen cloths secured in said pans of descending mesh sizes, the uppermost being the coarsest; means for carrying and keeping separate the respective screened sizes; 65 resilient contactable cushions secured to both the outer and inner frames, adapted in operation to give a positively resilient action to said inner frame; means for keeping evenly distributed the material going onto 70 said screens and means for imparting a rapid stroke or movement to said inner frame.

In testimony whereof I have hereunto set my hand in presence of two subscribing witnesses. 75

JOHN GIDEON KIRKSEY.
